APRON PANEL FOR GLIDERS

Isidore P. Smith, Perrysburg, Ohio, assignor to
The Hettrick Manufacturing Company, Toledo,
Ohio, a corporation of Ohio.

Application December 23, 1939, Serial No. 310,768

2 Claims. (Cl. 5—124)

This invention relates to articles of furniture but more particularly to gliders or couches of the type having a spring supporting structure on which seat cushions are loosely placed and having a panel of metal or other similar material covering a portion of the glider front concealing at least a portion of the spring supporting structure.

An object is to produce a structure of the above character in which the front apron panel can be readily and conveniently mounted without the use of bolts or nuts.

Another object is to provide a front apron panel for a glider or other similar article of furniture which can be applied to the frame parts by a snap action and which can be readily removed without the use of tools or separate fastening device.

Other objects and advantages will hereinafter appear and for purposes of illustration but not of limitation an embodiment of the invention is shown on the accompanying drawing in which

Figure 1 is a front perspective view of a glider showing the apron panel attaching means in dotted lines;

Figure 2 is an enlarged fragmentary perspective view of the front frame cross bar and apron panel attached thereto;

Figure 3 is an enlarged vertical sectional view of the apron panel and front frame bar of the glider and showing the clip carried by the apron panel in engagement with the cross bar, the parts being shown in dotted line position to indicate the manner in which the clip is applied to the frame cross bar;

Figure 4 is an enlarged perspective view of an end portion of the apron panel; and

Figure 5 is an enlarged fragmentary elevation of one end of the glider.

The illustrated embodiment of the invention comprises a glider having a supporting frame provided with a pair of upright end panels 10 to which are connected a pair of spaced substantially U-shaped tubes 11 so arranged as to support the end panels 10 in the desired position. As will be readily understood by those skilled in this art, the glider seat structure generally indicated at 13, is suspended from the upright end panels by pairs of pivotally mounted hangers 12, two being disposed at each side of the glider. The hangers 12 are pivotally connected at their lower ends to legs 14 depending from the seat frame

15. The detail construction of the seat frame is not considered necessary but as will be understood by those skilled in this art, it includes a

horizontally extending front bar 16 of angle iron and from opposite ends of the bar 16 extend rearwardly side angle bars 17.

Secured to the frame 15 is a coil spring supporting structure of the usual type made up of a series of crisscrossing wire rods suitably carrying vertically disposed coil springs 18 generally helical in shape but which taper from top to bottom, the smaller portion being disposed at the lower end. It will be understood that a sizable number of springs 18 are employed spaced laterally from each other and anchored at the top and bottom ends to a suitable frame work, all of which is well-known to those skilled in this art so that further description and illustration is not considered necessary.

At the rear end of the seat frame 15 is a suitable back frame (not shown) against which loosely rest cushions 19, in this instance three cushions being employed. Resting loosely on the coil spring supporting structure are suitable cushions 20 which are identical with each other and may be interchanged or reversed as desired. In this instance, a sheet metal panel 21 extends across the front of the glider and is disposed in upright position against the front frame cross bar 16. Preferably the panel 21 is of light gauge sheet metal, although it may be of any other suitable sheet material and as shown, a portion extends above and a portion below the frame bar 16. It will be noted that the upper portion of the apron panel 21 is disposed in front of and covers the lower portion of the spring supporting structure but the upper edge of the panel is located a substantial distance below the top of the coil springs 18.

The remaining exposed portion of the coil spring supporting structure is covered by a covering or envelope 22 of textile fabric or other suitable flexible material. If desired, the envelope 22 may cover only the front portion of the coil spring supporting structure. The lower portion of the cover of envelope 22 is disposed in rear of and below the top edge of the apron panel 21 and to insure that it will be held in the desired position, a hook 23 engages the lower edge of the cross bar 16 and is flexibly connected by a strap 24 to the covering 22. As shown, three hooks are provided at spaced intervals so that the covering 22 will be held in the desired position at all times throughout the front portion of the glider.

It will be manifest that spacing of the upper edge of the apron panel 21 below the seat cushions 20 is of importance since it enables a per-

son sitting upon the seat cushions to compress the coil spring supporting structure without hitting against the upper edge of the panel 21.

The apron panel 21 is retained in position by clips 25 which are secured, as by welding, to the rear face of the panel 21. In this instance, two clips 25 are employed although the number may be varied as desired. As shown, each clip 25 consists of a vertical portion 26 which is preferably secured by welding to the panel 21 and at the lower end of the portion 26 is an inwardly extending lip 27. From the upper end of the vertical portion 26 extends a horizontal portion 28 which terminates in a downwardly extending lip 29 which is considerably longer than the lip 27. The arms 26 and 28 of the clip are substantially equal in length to the width of the vertical and horizontal portions respectively of the angle iron cross bar 16. This enables the panel to be readily snapped into engagement with the cross bar 16 as indicated by the dotted line position of the parts on Figure 3. It is merely necessary to hook the lip 29 over the edge of rearwardly extending portion of the cross bar and then swing the apron panel downwardly so that the clip is snapped into place with the lip 27 engaging the edge of the vertical portion of the bar 16. The clips are preferably of sheet metal having sufficient strength and resilience to effect the desired snap action.

As shown, the opposite ends of the apron panel 21 are formed with rearwardly extending portions or wings 30, each having a notch 31 to afford clearance for glider parts disposed at opposite ends of the glider inside of the end panels 32. As indicated in Figure 5, at each end of the glider is an upright plate or panel 32 which has a horizontally disposed arm rest 33 at the upper end. Fixed to the plate 32 is a brace rod 34 which is detachably secured in any suitable manner to the adjacent side bar 17. Since the remaining detail structure of the mounting of the plate 32 forms no part of the present invention, further description and illustration is not considered necessary.

It is apparent from the above description that

the sheet metal apron panel 21 can be readily and conveniently mounted in position of use or detached as desired without the use of separate fastening device or special tools. In order to apply the panel to the frame bar 16, it is merely necessary to tilt it to the desired position in order to engage the clips 25 and then by a rocking motion, snap the clip into retaining position. The contact between the clips 25 and the angle bar 16 is sufficient to hold the panel securely in place against accidental displacement.

It is to be understood that numerous changes in details of construction, arrangement and operation may be effected without departing from the spirit of the invention especially as defined in the appended claims.

What I claim is:

1. In a glider having a seat frame mounted for swinging movement between laterally spaced upright interconnected end frames, said seat frame including an angle bar horizontally disposed across the front of said frame, a vertically disposed sheet metal panel extending across the front of said bar, and a series of inverted L-shaped clips fixed to the rear face of said panel between the top and bottom edges thereof, each clip having an integral lip at the free end of each arm of the L, one lip being longer than the other to afford snap-on engagement with said angle bar, said clip means providing the sole means whereby said panel is attached to said angle bar.
2. In a glider having a seat frame mounted for swinging movement between laterally spaced upright interconnected end frames, said seat frame including an angle bar horizontally disposed across the front of said frame, a vertically disposed sheet metal panel extending across the front of said bar, and a series of inverted L-shaped clips fixed to the rear face of said panel between the top and bottom edges thereof, each clip having an integral lip at the free end of each arm of the L, said clip means providing the sole means whereby said panel is attached to said angle bar.

ISIDORE P. SMITH.
